DISCHARGE TUBE

Huibert Gerard Boumeester, Eindhoven, Netherlands, assignor to N. V. Philips' Gloeilampenfabrieken, Eindhoven, Netherlands

Application December 28, 1936, Serial No. 117,965
In Germany December 30, 1935

5 Claims. (Cl. 250—27.5)

My invention relates to discharge tubes whose envelopes comprise a metal portion.

In tubes of such a construction, which are frequently used for both grid-controlled and uncontrolled rectifiers, it is desirable to screen the discharge path, and also in some cases one or more of the electrodes, from external influences. This has been effected in various manners, for example by screwing a metal screening member to the metal envelope portion, or by applying a conductive coating upon either the inner or outer surface of the envelope. The former method had the disadvantage that the screw threads became distorted when the glass envelope portions were sealed to the metal portion, whereas external coatings had the disadvantage that the insulating wall of the envelope reduced the screening effect.

Although internal coatings eliminated such reduction in the screening effect by the tube wall, it was very difficult to provide a suitable electrical connection. It has been proposed to connect such coatings to a lead sealed in the envelope, by means of a resilient ring connected to the lead and bearing upon the coating, or by means of a pool of liquid mercury; however such an electric contact with the coating was often defective or unreliable. Furthermore, the use of an additional lead through the envelope complicated and increased the cost of the tube.

The object of my invention is to eliminate the above difficulties and to provide a simple, inexpensive and effective screen for such tubes.

In accordance with the invention, I provide a conductive coating upon the inner surface of the envelope and extend this coating partly over the metal envelope portion so as to make a good electrical connection therewith.

Such a construction has the advantage that the conductive coating may be provided in a simple and inexpensive manner, and that no additional connections between the coating and a supply lead are necessary. Furthermore, the metal envelope portion, which may serve as a control or ignition electrode, also serves as the supply lead to the coating, thereby simplifying the construction.

Further advantages of my invention will appear as the description progresses.

In order that my invention may be clearly understood and readily carried into effect, I shall describe same more fully with reference to the accompanying drawing, in which the single figure is a sectional view of a grid-controlled rectifier tube.

The tube shown in the drawing has an envelope comprising a glass cathode portion 1, a glass anode portion 2, and an annular metal portion 3 provided with a cross shaped radial partition 15 and hermetically sealed between the glass portions. The metal portion 3 serves as a control electrode and has secured to it by means of a clamp ring 14, an external lead 10. The filling of the tube may consist of one or more gases, vapors or a mixture thereof. In the present instance, a drop 11 of mercury is arranged in the lower part of the vessel to provide a mercury vapor filling.

Hermetically sealed in the bottom of portion 1 are two chrome iron plates 12, to which are secured two conductive supports 4, carrying on their ends an incandescent cathode 5. The supports 4 are connected through the plates 12 to external supply leads 13 secured to plates 12, and are supported at intermediate points by two cross members insulated by glass beads 8. Within the portion 2 and supported by a conducting rod 6 carried by a plate 12 sealed in the envelope, is an anode 7.

Upon the inner surface of the upper portion 25 of the glass portion 1 and extending over the inner surface of metal portion 3, is a layer or coating 9 of conductive material. As the material of the layer 9, I prefer to use colloidal graphite, which can be applied in a simple manner from a commercial aqueous solution, for instance the solution known under the trade name "aquadag". Silver is also very suitable for use as the coating as it can be quite readily precipitated upon the glass wall by any of the well-known methods. 35 However, as silver is attacked by mercury such a coating cannot be used alone in tubes provided with a filling containing mercury vapor.

In such cases I provide the silver coating, for example, by an electroplating process, with a protective layer of a metal which amalgamates with mercury only with difficulty. As such a protective layer—indicated by 15 in the drawing—chromium or nickel may be used.

It will be noted that the metal portion 3 serves 45 two functions, namely, as an ignition or control electrode, and as a connection to the conductive coating 9 serving as an electrostatic screen for the cathode 5 and for a portion of the discharge path. Furthermore, an excellent electrical connection is obtained between the coating 9 and the metal portion 3 without additional means, and it is unnecessary to provide an additional connection through the tube wall.

While I have described my invention in connec- 55

tion with incandescible cathode discharge tubes, it is not limited thereto but is applicable to discharge tubes in general, whether of gas filled or high vacuum type, and having either an incandescible, mercury, or cold cathode. Therefore I do not wish the appended claims to be limited to the embodiment described, but desire same to be construed as broadly as permissible in view of the prior art.

10. What I claim is:

1. A discharge tube comprising an envelope having a metal portion and a vitreous portion hermetically sealed together, electrodes within said envelope, a conductive coating upon part of the inner surface of said vitreous portion and extending over part of the inner surface of said metal portion, and a terminal for said coating connected to the outside of said metal portion.

2. A discharge tube comprising an envelope having a vitreous anode portion, a bell-shaped cathode portion, and an annular metal portion hermetically sealed between said vitreous portions and serving as an electrode, an anode disposed within said anode portion and a cathode disposed within said cathode portion to form a discharge path, and a conductive layer upon a portion of the inner surface of said cathode portion and extending over part of the inner surface of said metal portion, said coating forming 30 a bell-shaped screen surrounding said cathode

and the portion of the discharge path between said cathode and metal portion.

3. A discharge tube comprising an envelope having a metal portion and a vitreous portion hermetically sealed together, a filling comprising mercury vapor, electrodes within said envelope, a layer of silver upon part of the inner surface of said vitreous portion and extending over part of the inner surface of said metal portion, and a protective coating covering said silver layer, said coating being of a metal substantially unaffected by mercury.

4. A discharge tube comprising an envelope having a metal portion and a vitreous portion hermetically sealed together, a filling comprising mercury vapor, electrodes within said envelope, a layer of silver upon part of the inner surface of said vitreous portion and extending over part of the inner surface of said metal portion, and a protective coating of chromium upon said silver layer.

5. A discharge tube comprising an envelope having a metal portion and a vitreous portion hermetically sealed together, a filling comprising mercury vapor, electrodes within said envelope, a layer of silver upon part of the inner surface of said vitreous portion and extending over part of the inner surface of said metal portion, and a protective coating of nickel upon said silver layer.

HUIBERT GERARD BOUMESTER. 30
